 Field Company, Boston, Mass.

Application April 25, 1942, Serial No. 440,522

3 Claims. (Cl. 51—92)

This invention relates to sharpening or grinding apparatus, and more particularly to mortise chain cutter sharpening apparatus.

The invention and its aims and objects will be readily understood from the following description, taken in connection with the accompanying drawings, of one embodiment of the invention herein given for illustrative purposes.

In the drawings:

Fig. 1 is a front elevation of one illustrative embodiment of the invention;

Fig. 2 is a top plan view of the embodiment shown in Fig. 1, partly in section on line 2—2 of said figure;

Fig. 3 is a top plan view of the embodiment of the invention shown in Fig. 1;

Fig. 4 is a longitudinal section on line 4—4 of Fig. 3;

Fig. 5 is an enlarged longitudinal section on line 5—5 of Fig. 3;

Fig. 6 is a sectional elevation on line 6—6 of Fig. 4, on a somewhat enlarged scale;

Fig. 7 is a cross section on line 7—7 of Fig. 5;

Fig. 8 is a side elevation of the parts shown in Fig. 3, on a somewhat enlarged scale, certain parts being shown in section on lines 8—8 and 8a—8a of Fig. 7;

Fig. 9 is a side elevation of the sprocket with the mortise chain thereon, on a somewhat enlarged scale as seen from the right of Fig. 1, and showing the general operative position of the grinding or sharpening tool;

Figs. 10 and 11 show how the hook or angle of the cutting edge of cutters may be varied as desired.

In the illustrative embodiment of the invention herein shown, the frame 2 is provided in front with a vertical guide-slot 4, in which a correspondingly shaped guide-rib 6, provided upon a support or carriage 8, has a sliding fit. Said carriage 8 carries a clamping bearing 10 for a shaft 12. To the projecting ends of said shaft 12 are secured the free ends of arms 14 of a bracket 16 which supports the means for presenting the mortise chain to said grinding or sharpening tool, said means herein illustratively comprising a shaft 18 slidably and rotatably mounted in said bracket and having a reduced end portion 20 upon which is fixedly secured a sprocket 22 (see Fig. 6). A rod 24 is provided at one end with a reduced, screw-threaded portion 26 having screw-threaded engagement with an axial bore 28 in said end portion 20 of said shaft 18. Tightening the screw-threaded engagement of said rod 24 with said shaft 18 will firmly secure the former to the latter and will firmly clamp said sprocket 22 to said shaft between a collar 30 on said rod 24 and a shoulder 32 on said shaft 18 so that said sprocket will slide and turn with said shaft and rod 24. The latter may be provided at its free

end with a wheel 34 to facilitate manipulation thereof.

The sharpening or grinding means herein illustratively comprises a sharpening or grinding tool, 5 which may illustratively consist of a disk shaped grinding wheel 36 positioned above and to the left, see Fig. 1, of the said sprocket 22 when said rod 24 is in its extreme position to the right, as shown in said figure. Said grinding wheel may be driven by any suitable driving means. Herein said wheel is conveniently driven by an electric motor 38, mounted upon the frame 2, and preferably provided with a hood 40 enclosing the same sufficiently to protect the operator from flying particles from said wheel and the work.

To grind the cutters of a mortise chain, the latter, herein designated by 41, is suspended upon said sprocket 22 (see Fig. 1) with teeth of the latter in mesh with links of said chain, and 10 grinding or sharpening of the cutter teeth is effected by sliding said rod 24 and shaft 18 back and forth so as to reciprocate said sprocket and chain carried thereby past said rotating grinding wheel 36, and turning said rod, shaft and sprocket 15 step by step so as to bring all the cutters of said chain successively into grinding position relatively to said disk (see Fig. 7).

Heretofore the mortise chain to be sharpened was sustained only by the sprocket from which it hung perfectly free, with the result that there was a complete lack of stability or control of the chain and its cutters. To remedy this it has therefore always been customary for the operator to grasp and hold the mortise chain with one hand while operating the rod 24 with the other, during the sharpening operation. In order to be effective, however, this required that the mortise chain be grasped as closely as feasible to the sprocket 22, which not infrequently resulted in 20 injury to the operator's hand. Furthermore neither the position of the chain nor the tension exerted thereon was uniform during the sharpening operation so that all the cutters of the chain were not ground uniformly and were therefore 25 not of the same length and the same degree of hook. As a result of this lack of uniformity in the sharpening of the cutters some of the latter could not perform their share of the mortising operation, which detracted from the appearance and perfection of the mortise. The sharpening of the cutters as heretofore practised required an expert operator and even so the result was not 30 uniformly satisfactory.

One of the objects of the present invention is to remedy these defects and to that end means are provided for controlling the mortise chain during the cutter grinding or sharpening operation. The position of the mortise chain may thus be controlled, for example with relation to the 35 means for presenting the chain to the cutter

grinding or sharpening means, so that said position shall remain substantially the same during the sharpening of all the cutters of the chain. Preferably the arrangement will be such that the chain will be under tension, and means may be provided in accordance with the present invention whereby the tension may be adjusted or regulated as may be desirable; the tension may be adjusted so that it shall be the same as that to which the chain will be subjected while in operation on the mortising machine.

Referring to Figs. 1 and 6, said means for controlling the position of the mortise chain herein illustratively comprises a bar 42 loosely suspended by one end 44 from said shaft 18, for example, and between said sprocket 22 and a collar 46 upon said shaft. A block 48 provided with a guide roll 49 is slidably mounted upon said bar 42. A second block 50 is also mounted upon said bar 42 and is adjustable lengthwise thereof, a set screw 52 serving to clamp said block 50 in adjusted position. This bar acts as a support. A spring 54 surrounds said bar and bears with one end against block 48 and with the other against block 50. Means is thus provided for putting the chain under tension or for holding it yieldingly in position. The guide roll 49 will preferably be centered, or crowned or biconical in cross section, to accommodate chains of different width.

The lower end of said bar 42 engages a longitudinal slot or guideway 56 in a slotted member 58 rigidly secured to a fixed portion of the apparatus. Herein said slotted member is conveniently secured to the rear surface of the hood 40 of the grinding tool, by a rod or bar 60. Means is thus provided to guide said controlling means and prevent bodily movement of the mortise chain transversely to shaft 18, while permitting said chain to move with said shaft 18 in its longitudinal movement as required to move the chain and sprocket past the grinding tool in the grinding or sharpening operation.

Means may be provided to facilitate adjustment of the tension to be exerted upon said mortise chain 41. Herein said means may conveniently comprise an index or pointer 62 carried by one of the blocks 48 or 50, and a tension scale 64 carried by the other of said two blocks and bearing graduations indicative of different degrees of tension.

Said shaft 18 is slideable and rotatable in a bearing 66, and a further bearing 68 is provided to be engaged by the inner end of said shaft 18 when the latter is moved to the left (see Fig. 5). Said bearing 68 is contained in a tubular member 70 rotatably fitted at its inner end within an enlarged part 72 of said bearing 66, and herein the rotatable tubular member 70 is provided interiorly with longitudinal grooves 76. Said shaft 18 is provided with a head 78 upon the outer surface of which are splines 80, parallel to said grooves 76 and adapted to slide into locking engagement with the latter to guide said shaft 18 and the cutter to be sharpened in the right paths when the sprocket is moved past the grinding tool to sharpen said cutter, and to lock said shaft 18 and sprocket 22 against rotation during this operation. The spacing of the cutters on the mortise chain is such that when said chain is on the sprocket 22 a cutter will be opposite each sprocket tooth and opposite each space between two sprocket teeth. There should therefore be twice as many grooves 76 and twice as many splines 80 as there are teeth on the

sprocket. Herein the sprocket used has 7 teeth and there are therefore 14 grooves 76 and 14 splines 80. Whenever the splines 80 are in mesh with grooves 76 a cutter of the mortise chain on the sprocket will be in position to be moved past the grinding tool and be sharpened.

That portion of shaft 18 between the upper end 44 of bar 42 and the right end (see Figs. 1 and 5) of said bearing 66 will preferably be enclosed by a seal of any suitable flexible material 82. The ends of said seal 82 are fitted over flanges 84 and 86 respectively on said bearing 66 and on said top portion 44 of said bar 42. Said shaft 18, its bearing 66 and the grooves 76 and splines 80 will thus be kept free from dust and dirt and particles cast off from the grinding wheel 36 and from the mortise chain cutters in the grinding operation. Grooves 88 and 90 may be provided in said flanges 84 and 86 respectively, and the end portions of said seal may be tightly bound in said grooves by bands or wires 92, 94 to provide a very thorough seal. An oil cup for shaft 18 is shown at 96; other oil cups (not shown) are provided at all points where required.

Vertical adjustment of the sprocket 22 and associate parts is provided for by suitable means, herein illustratively comprising a regulating screw 98 in threaded engagement with a vertical bore provided in the top of frame 2 (see Fig. 1), and suitably mounted in an arm 100 of the carriage 8. A wheel 102 will preferably be provided to facilitate manipulation of said screw 98. Means are also provided for varying the hook or angle of the cutting edge imparted to the cutters of the mortise chain. Herein said means illustratively comprises a relatively fine threaded adjusting screw 104 in screw threaded engagement with a boss 106 upon the under side of bracket 16. The free end of said screw 104 abuts against the front face of said guide rib or slide 6. By loosening the clamping device comprising handle 108 and clamping screw 110 extending through flanges 112 and 114 of the clamping bearing 10, the shaft 12 carrying said bracket will be freed, thus permitting swinging adjustment of said bracket 16 about the axis of said shaft 10 to vary the hook or angle imparted to the chain cutters, whereupon said clamping device may be tightened to lock said bracket 16 in adjusted position. A scale 116 may be provided upon the upper surface of one of the arms 14, and a line 118 upon the adjacent edge portion of the bearing 10, to facilitate adjustment of the parts to obtain the desired hook or angle of the cutter edge (see Fig. 3).

Means may also be provided for varying the length of the cutters of the mortise chain. Herein this is provided for by adjustment of said tubular member 70 about its longitudinal axis by rotating said tubular member 70 and thus angularly to adjust said guide grooves 76 clockwise or counterclockwise. Said member 70 is held in adjusted position by clamping means comprising a shoe 120 slidably mounted in a recess provided in said bearing 66 and slideable along a screw 122 fixed in the wall of said bearing 66 opposite the inner end of said shoe 120. The free end of said screw projects beyond the right end (see Fig. 8) of said shoe 120 and is in screw threaded engagement with one arm of an angular hand lever 124. By turning said lever 124 in the proper direction said clamp will be released and said member 70 may be rotated about its axis angularly to adjust said grooves 76 to vary the length of the mortise chain cutters, and member

70 then may again be clamped in its new position. To facilitate angular adjustment of said grooves 76, said tubular member 70 may be knurled exteriorly as shown at 126 in Fig. 1.

The operation is briefly as follows:

The mortise chain having been placed upon the sprocket 22 and the guide roll 49, and all adjustments as above set forth, having been made, the motor is started thus setting the grinding wheel in operation. The shaft 18 being in its extreme right position, with the sprocket 22 substantially in the position shown in Fig. 1, the operator grasps the wheel 34 and slides rods 24 and shaft 18 to the left in said figure. In this movement splines 80 upon head 78 of shaft 18 first engage grooves 76 in member 70, which is immobilized by the clamping device 120, 122, 124, as above described, and then slide along in said grooves as the sprocket 22 with the mortise chain thereon moves past the grinding wheel 36 to sharpen a cutter by contact with the latter, said cutter being guided in the correct path by engagement of said splines 80 with said grooves 76. The operator now draws rod 24 and shaft 18 to the right (see Fig. 1), thus disengaging splines 80 from grooves 76, the sprocket 22 thus occupying substantially the position shown in said Fig. 1. The operator then turns said shaft and sprocket clockwise through the distance separating grooves 76 from one another. This brings each of the splines 80 in line with that groove 76 which follows the groove 76 it was previously in engagement with, so that by now moving shaft 18 and sprocket 22 to the left, the next mortise cutter will be guided past the grinding wheel and sharpened by contact with the latter. This same procedure is followed for the next cutter on the mortise chain and so on until all the cutters on said chain have been sharpened. During this entire operation the mortise chain and the cutters thereon are held in correct position by the mortise chain controlling means, and preferably under the same tension, substantially, as that under which said chain will be held in the mortising machine during the mortising operation.

Applicant's invention is a distinct advance in the art and a valuable contribution thereto. The mortise chain is under perfect control during the sharpening operation, thereby ensuring uniform grinding and sharpening of the cutters of said chain, and consequently more uniform and perfect work in the mortising operation. Any seven tooth, standard sprocket may be used. Instead of using both hands, as was heretofore necessary, the operator need use but one. The operator need not be an expert, as heretofore, and the sharpening operation is from twice to three times as fast as heretofore. Operating with shaft 18 and the mortise chain under tension, preferably the same tension as that to which said chain is subjected in the mortising machine, ensures longer life for the mortise chain, greater accuracy and smoother operation.

I am aware that the present invention may be embodied in other specific forms without departing from the spirit or essential attributes thereof, and I therefore desire the present embodiment of said invention to be considered in all respects as illustrative and not restrictive, reference being had to the appended claims rather than

to the foregoing description to indicate the scope of the invention.

I claim:

1. Apparatus for sharpening cutters of endless cutter chains, comprising cutter sharpening means; a sprocket and a guide roll over which to train an endless cutter chain; said sprocket and guide roll being adapted to move relatively to said cutter sharpening means to present a cutter of said chain to said cutter sharpening means; supporting means for said guide roll, said supporting means comprising a member carrying said guide roll and movable toward and from said sprocket; a second member adjustable relatively to said first named member upon said supporting means; a spring adapted to bear with its opposite ends against said two members respectively; means for securing said second member in adjusted position upon said supporting means; means for moving said sprocket relatively to said cutter sharpening means to sharpen a cutter of a cutter chain upon said sprocket; and means for moving said guide roll relatively to said sharpening means with said sprocket.

2. Chain cutter sharpening apparatus comprising a cutter sharpening tool; a cutter chain carrier comprising a shaft and a sprocket mounted on said shaft, said shaft being rotatable and slidable longitudinally to present a chain cutter on said sprocket to the operation of said cutter sharpening tool; a support for said shaft; locking means, including corresponding projections and grooves on said shaft and its support, concentric with said shaft and coacting therewith positively to hold said shaft against rotation during the cutter sharpening operation, said shaft being rotatable relatively to said locking means when said cutter chain carrier is in a non-sharpening position; and cutter chain tensioning means, including means to hold said chain under resilient tension, adapted to engage said chain, said shaft being operatively connected to said cutter chain tensioning means, whereby said shaft will move said cutter chain tensioning means with said sprocket when said shaft is moved longitudinally.

3. Chain cutter sharpening apparatus comprising a cutter sharpening tool; a cutter chain carrier comprising a shaft and a sprocket mounted on said shaft, said shaft being rotatable and slidable longitudinally to present a chain cutter on said sprocket to the operation of said sharpening tool; a support for said shaft; locking means, including corresponding projections and grooves on said shaft and its support, concentric with said shaft and coacting therewith positively to hold said shaft against rotation during the sharpening operation, said shaft being rotatable relatively to said locking means when said cutter chain carrier stands in non-sharpening position; and cutter chain tensioning means adapted to engage and to keep said chain under resilient tension, said shaft being operatively connected to said cutter chain tensioning means, whereby said shaft will move said cutter chain tensioning means with said sprocket when said shaft is moved longitudinally; and guiding means to guide said cutter chain tensioning means when moved by said shaft.

LEWIS W. ENHOLM.
